UNITED STATES PATENT OFFICE.

WILLIAM T. CARROLL AND EDGAR J. CARROLL, OF WORCESTER, ASSIGNORS
TO THE EUREKA SPINDLE COMPANY, OF AYER, MASSACHUSETTS.

SPINDLE-BOLSTER.

SPECIFICATION forming part of Letters Patent No. 340,656, dated April 27, 1886.

Application filed December 28, 1885. Serial No. 186,833. (No model.)

To all whom it may concern:

Be it known that we, WILLIAM T. CARROLL and EDGAR J. CARROLL, citizens of the United States, and residents of Worcester, in the county of Worcester and State of Massachusetts, have invented certain new and useful Improvements in Spindle-Bolsters; and we do hereby declare the following to be a full, clear, and exact description thereof, reference being had to the accompanying drawings.

Our invention relates to that class of bolsters in which all the bearings for the spindles are integral; and it consists, essentially, in attaching or connecting the bolster to the bolster-rail in a yielding or flexible manner, such attachment preferably being at one point only, and that point being located outside of or eccentric to the axis of rotation of the spindle, the object of such construction being to enable the spindle to run steadily at high speed, and also to prevent the communication of jar or vibration from the bolster-rail to the spindle.

Heretofore bolsters of this class having a yielding capacity or attached to the bolster-rail in a flexible manner have been connected to the bolster-rail at more than one point of attachment, such points being arranged at or around the axis of rotation of the spindle, and all yielding which took place being about such axis as a center of motion. In this our improvement, however, the point of attachment is wholly on one side, or eccentric to such axis, and the motion of the bolster is about a new and independent center which is thereby established, and a greatly improved result is accomplished. This improved result is in part due to the fact that the center of motion being located at one side or away from the spindle and its bearings, the same degree of freedom at such distant point will afford the spindle a much greater degree of movement or adjustment by reason of the distance between such point and the spindle.

Referring to the drawings, Figure 1 is a central sectional elevation, showing the spindle and its sleeve-whirl, the sectional bolster, and the bolster-rail in detail; Fig. 2, a like view, showing a modification in the method of connecting the sections of the bolster together.

In Fig. 1 it will be seen that the lower section or bolster-base, A, is attached to the bolster-rail B in the usual manner. It extends backward over the rail and is provided with the drop or downward extension *a*, which is drilled to form a socket for the pin *p*. The upper section, C, having the supporting tube *c*, which receives and supports the spindle *s*, is attached to the lower section by means of the pin or stud *p*, which is firmly attached to the upper section, but is loosely fitted within the socket formed for it in the extension *a*. The yielding washers *d* and *e* are placed between the upper and lower sections, and the pin *p* may be cushioned by means of oil or other yielding packing placed around it in its socket. The screw *r* serves to prevent the upper section from being raised in doffing, and is provided with a yielding washer, *t*, under its head. The cavity *f*, formed in the lower section, receives the extension *g*, formed on the under side of the upper section, and allows the foot of the spindle to be extended downward, as shown.

In Fig. 2 the parts *a* and *p* are reversed, the pin extended upward and attached to the lower section, while the socket *a* is attached or formed on the upper section and sleeves upward around the pin, fitting it loosely, as before. This arrangement has the advantage that it brings the pull of the band midway of the pin and socket, and does not tend to deflect the spindle from the perpendicular. We therefore consider this form or arrangement as the most desirable one to carry out our improvement.

Having thus described our invention, what we claim is—

1. A spindle and its sleeve-whirl, a combined bolster and step for such spindle, provided with a supporting arm or extension, a bolster-base adapted to be attached to the bolster-rail, as usual, and a connecting pin or stud located outside of or eccentric to the axis of the spindle, and adapted to connect the said bolster and base and support the bolster against the band-pull, as set forth.
2. A spindle and its sleeve-whirl, a combined bolster and step for such spindle, hav-

ing a vertical tube or socket formed on the base of the bolster at a point eccentric to the axis of the spindle, a bolster-base adapted to be attached to the bolster-rail, as usual, and 5 provided with a fixed pin or stud adapted to enter the said tube or socket and support the bolster therefrom, as set forth.

In testimony whereof we have hereunto set

our hands in the presence of two subscribing witnesses.

WILLIAM T. CARROLL.
EDGAR J. CARROLL.
